UNITED STATES PATENT OFFICE.

RUDOLPH F. STAHL, OF BOSTON, MASSACHUSETTS, ASSIGNOR TO THE BOTTLERS MACHINERY COMPANY, OF SAME PLACE.

LABELING-MACHINE.

SPECIFICATION forming part of Letters Patent No. 680,986, dated August 20, 1901.

Application filed October 22, 1898. Serial No. 694,268. (No model.)

To all whom it may concern:

Be it known that I, RUDOLPH F. STAHL, of Boston, in the county of Suffolk and State of Massachusetts, have invented certain new and useful Improvements in Labeling-Machines, of which the following is a specification.

This invention has relation to machines for pasting labels upon bottles, cans, boxes, or other articles, and has for its object to provide certain improvements in the same, whereby the labels may be more expeditiously and firmly affixed to articles of different sizes and shapes and whereby the machines themselves may be rendered more simple in construction and more highly efficient in operation than heretofore.

It has further for its object to provide for the stamping or printing upon the labels as they are being affixed of certain data or information, such as the date, the name of the liquid in the bottle or receptacle, or the name of the bottler or person using the machine.

Inasmuch as some labels are longer than others or are made of different kinds of paper, glazed and unglazed, it is desirable at times, especially when the label is longer than one-half the circumference of the bottle, to paste it only at the ends, and therefore another object of the invention is to provide mechanism whereby labels of all kinds may be placed upon their receptacles with equal facility and whereby their ends will be pressed against the surfaces of the bottles, cans, or other receptacles.

To this end the invention consists of a machine possessing certain features of construction and arrangement of parts which may be employed in combination or separately, all as is illustrated upon the drawings and now to be described in detail, and pointed out in the claims hereunto annexed.

Reference is to be had to the accompanying drawings, and to the letters marked thereon, forming a part of this specification, the same letters designating the same parts or features, as the case may be, wherever they occur.

Of the drawings, Figure 1 represents in front elevation a labeling-machine embodying my invention. Fig. 2 represents the same in side elevation. Fig. 3 represents a longi-

tudinal section taken on the line 3 3 of Fig. 1. Fig. 4 represents a partial sectional view of one of the wipers and its adjuncts. Fig. 5 represents a plan view of the same, Figs. 55 4 and 5 showing the parts on a large scale.

Referring to the drawings, I have illustrated the machine which I have selected as best showing one embodiment of the invention, and although I shall now proceed to describe the same more or less minutely it will be understood that I do not wish to be construed as limiting myself to the particular combination of parts or to the employment of the said parts in combination, as different portions of the machine may be used separately and many changes may be made in the same without departing from the spirit and scope of the invention.

The machine is best adapted for affixing labels to cans, as well as glass bottles of various sizes and shapes; but it may be changed to adapt it for many other uses and purposes when desired. It is constructed with a frame having side standards *a a*, connected by cross-braces *a' a'*, as shown in Fig. 1.

The frame may be formed in any shape consistent with lightness and strength and adapted to receive and support the various movable parts which are required for gumming a label and affixing it smoothly to a bottle or other receptacle. In the upper part of the frame a power-shaft *b* is journaled in suitable bearings *a² a²*, formed on the side standards *a*, power being applied to the shaft by means of a pulley *b'* or by any other desired means. From this shaft power is transmitted to the movable parts of the machine.

Pivoted upon a shaft *c*, mounted in the upper portion of the machine and secured in the standards *a*, is a cam-actuated lever *c'*, having on its inner end a roller extending into engagement with a cam *c¹²*, rigidly secured to the power-shaft *b*. Pivoted to and depending from the outer end of the lever *c'* is a label-carrier, which, as shown, consists of the slotted bar *c²*, formed at its lower end with studs *c³* to extend into apertures in two oppositely-movable arms *c⁴*. The said arms *c⁴* hang loosely from the bar *c²*, being connected by a spring *c¹⁰*, and are provided with extensions or stops *c⁵* to abut against adjustable

screws c^6 , which limit the inward movement of their lower ends, the said screws being threaded through lugs c^7 , as shown in Fig. 1, on the lower end of the bar c^2 . Upon the 5 lower ends of the arms c^4 are secured label-carrying shoes c^8 , which may be of any material suitable for the purpose. By means of the lever c^1 and its cam the label-carrier is raised and lowered, and through the medium 10 of the devices which I shall now describe it is swung bodily about its pivot to receive a label and deposit it upon a bottle. To the bar c^2 is connected a slide d , having its slotted or forked end extending past the power- 15 shaft b , as shown in Fig. 3, and having a roller d^1 projecting into a cam-slot in a cam-disk d^2 , secured to the power-shaft b . In the path of the label-carrier is placed the tank or receptacle e for the gum or paste which is 20 used for sticking the label to the bottle or other receptacle. The tank rests upon adjusting-screws e' , threaded through lugs a^5 a^5 , projecting inwardly from the standards a of the frame, there being lock-nuts e^2 on the 25 screws e' to lock them after they have been once adjusted. The tank is filled with any desirable paste or gumming material, and partially submerged therein is the paste-distributing roller or rollers. As shown, I employ a 30 single roll f , equal in length to the label to be employed; but two separated rollers for applying a thin strip of paste at each end of the label may be used instead.

The shaft f' for the roller or rollers is 35 formed at one end with a toothed wheel f^2 , shown as coincident in diameter with the roll f . The label-carrier is provided with a downwardly-projecting rack or arm f^3 , having teeth to engage the toothed wheel, so that 40 when the label-carrier swings to the rear the rack comes in contact with the toothed wheel f^2 and rotates the paste-roll. In order to regulate the pressure of the shoes against the paste-roll, the carrier is provided with a roll 45 f^4 , which rides upon a cam spur or projection f^5 , projecting rearwardly from a bracket a^7 , secured to one of the side standards a . This construction and arrangement insures that 50 the paste will be distributed evenly on the surface of the label-carrying shoe.

In the rear of the tank is placed the label-box, which, as shown, consists of a plate g , having uprights g' to receive the labels. It is mounted on a plunger drawn upward automatically by a weight g^2 . The plate g is 55 mounted upon the end of a lever g^3 , fulcrumed at g^7 in the standards a of the frame and having at its upper end a roller bearing against a cam rigidly secured to the power-shaft b . The plunger is in a cylindrical guide g^8 and is locked normally against movement 60 by a lever g^4 .

An arm or bracket on the label-carrier before referred to is provided with a projection 65 in the shape of a screw f^{15} , which, after the label-carrier has reached its rearward limit, engages a pin g^6 and depresses it sufficiently

to operate the lever g^4 , and thereby unlock the piston k' and allow the weight g^2 to force it and the labels up against the gummed shoes 70 of the label-carrier. When the pin g^6 is disengaged from the projection f^{15} , the locking-lever immediately engages the piston to lock it against further movement. The label-box and the pin g^6 are normally out of the plane 75 of the shoes on the label-carrier, so that when the label-carrier has reached its rearmost position in alinement with the label-box the cam operates the lever g^3 to elevate the said label-box and bring the pin g^6 into engagement with the projection f^5 of the label-carrier, and before the label-carrier begins its forward movement the label-box is depressed. 80 Mounted to slide in a guide a^6 , projecting outward from the top of the cross-bar a' , and 85 in the end of the arm a^7 , projecting outward from one of the standards a , is a plunger h . It is reciprocated by a lever h' , fulcrumed at h^2 and operated by a cam-slide h^3 , embracing the power-shaft b , as illustrated in Fig. 3, 90 said slide having a roller projecting into a cam-slot in a cam h^4 on the power-shaft b . Immediately below the upper plunger is a lower plunger, table, or rest i , having its upper end formed to receive the bottle, can, or 95 other receptacle which is being labeled. It fits within a reciprocating tubular bar i' , sliding in a guide i^2 , secured to the front of the machine. A cushioning-spring i^3 is interposed between the lower end of the plunger i and 100 the bottom of the socket in the bar i' , as shown in Fig. 3. The plunger is reciprocated by mechanism including an arm i^4 , engaging a roller i^5 on the bar i' , which projects through a slot in the guide i^2 , said arm being mounted 105 on a rock-shaft i^6 . The power-shaft b on its end has a crank k , to which the crank-pin k' is adjustably secured, and a connecting-rod k^2 connects said pin with a pin i^7 , adjustably secured in a slotted arm i^8 , rigidly affixed to 110 the rock-shaft i^6 . By this arrangement of parts the rotation of the power-shaft effects a reciprocation of the plunger, the play thereof being varied as desired.

For the purpose of wiping the label upon 115 the bottle or other receptacle I provide the following devices: m m' indicate arms fulcrumed upon studs m' m' , projecting forward from webs i^9 , which extend laterally from the tubular guide i' . Wipers m^2 , formed of rubber or other suitable material, are supported by these arms and are adapted to engage the ends of the label and wipe them in an opposite direction upon the bottle, said wipers being arranged to yield in several directions to 120 accommodate bottles of various sizes and shapes. Each wiper is formed with two lips m^3 m^4 , the latter of which performs the initial wiping while the former completes the operation, especially where the label is greater 125 in length than one-half the circumference of the bottle or can. Said wipers are secured in holders m^5 , which are recessed to receive them and which are also formed with in-

wardly-extending tongues m^6 to take into longitudinal grooves in the top and bottom faces of the wipers. Studs m^7 project from the ends of each holder and are socketed at the extremities to receive inwardly-extending conically-pointed screws m^{10} , passed through the arms of a yoke n , which is pivoted by a stud n' to a lug m^8 on the end of the arm m . Each holder is free to swing upwardly, but is held against downward movement by a pin n^2 , projecting forward from the center of the yoke and overlapping a lug m^9 on the holder. On its end each arm m is extended laterally to support guide-pins n^3 , which pass through slots in the yoke at points equidistant from its pivot-stud n' , there being spiral springs n^4 coiled about said pins and tending to normally hold the yoke in a central position, so that the two wipers are parallel. By this arrangement of parts the wipers will yield upwardly and likewise laterally about the pivots n' to wipe a label upon a conical or otherwise irregularly-shaped bottle, can, or similar receptacle. Pivoted upon the studs m' are arms o , bent at their upper ends, as at o' , to form stops for the purpose of limiting the extent of inward movement of the wipers, and said arms may be adjusted about said studs and then secured in place by bolts o^2 , passed through the lower ends of said arms and through curved slots in the webs i^9 on the guide i^2 . Bent levers p are pivoted between their ends by pivots $p' p'$ in the extremities of said webs, and their upper and outwardly-projecting ends are formed to receive the lower ends of springs $p^2 p^2$. These last-mentioned springs have each several coils to increase its strength and resiliency, and they bear against the upper ends of the arms m , lying between two lugs m^{12} thereon, whereby the wipers are held yieldingly in position to engage the articles being labeled. Where the labels are longer than one-half the circumference of said articles it is generally difficult to wipe the ends thereof upon the latter, as the movements of the top and bottom plungers is quite rapid. Hence I secure to the lower plunger i a cam q , adapted to engage rollers $p^3 p^3$ on the lower ends of the levers p' , and swing said wipers inward just as the bottle is half-way past them, whereby they accomplish an extra or additional wiping of the ends of the label. The tubular bar i' and the guide i^2 are slotted to receive shouldered screw-pins p^4 , which secure the cam to the plunger, said cam being slotted to receive said pins and being thereby adjustable with respect to said plunger to cause the actuation of the arms at different times in accordance with the size or style of bottle or can that is being labeled. It will be understood that where the labels are comparatively short it is unnecessary that the secondary or auxiliary mechanism should be operated to increase temporarily the strength of the springs. In addition to these features I provide mechanism for printing, impressing,

or otherwise marking upon the backs of the labels the date, a trade-mark, or data of any kind. A type bar or lever r is fulcrumed at r' in lugs $a^9 a^9$ on one of the standards a' , and its arm is long enough to cause the type in the holder r^2 , adjustably secured thereon, to strike the top label in the label-box when said bar is swung downwardly. The type may be removably secured in the holder in any suitable way. The short arm of the bar or lever projects through the standard a and is pivotally connected by a stud r^4 to a curved link r^5 , which is in turn pivoted by a stud r^5 (at 80 right angles to the stud r^4) to an extensibly-adjustable rod r^6 , whose other end is pivoted by a stud r^7 to the strap r^8 of an eccentric s . The said eccentric s is loose upon a stud-shaft s' and is secured to or forms a part of a pinion s^2 , adapted to be intermittently engaged by a gear-segment s^3 on the main shaft b . The parts are so timed that when the label-carrier has picked up a label and carried it forward the type-bar will be swung downwardly with a quick motion to cause the type to engage the top label in the label-box. An inking-roller t is journaled in a yoke t' , extending laterally from the label-carrier, and when the latter swings forwardly the inking-roller impinges against the type on the type-bar.

Having thus explained the nature of my invention and described a way of constructing and using the same, though without attempting to set forth all of the forms in which it may be made or all the modes of its use, what I claim, and desire to secure by Letters Patent, is—

1. A labeling-machine comprising suitable mechanism for gumming and presenting a label, spring-tensioned separable wipers adapted to wipe the label on a bottle or can, and means supplemental to said springs for causing said wipers to wipe the ends of a label greater in length than one-half the circumference of the bottle.

2. A labeling-machine including wipers, means for operating the wipers, and auxiliary means for imparting an additional movement to the wipers toward each other.

3. A labeling-machine including wipers, springs bearing against said wipers, and means supplemental to the bottle or can for increasing the tension of said springs as the bottle or can passes between said wipers.

4. A labeling-machine, comprising wipers, movable toward and from each other, supports for said wipers, levers mounted independently of said supports, springs carried by said levers and bearing upon said wipers, and mechanism for actuating said levers.

5. A labeling-machine comprising wipers, movable toward and from each other, arms supporting said wipers, levers, springs on said levers bearing against said arms, and mechanism for actuating said levers.

6. A labeling-machine comprising a cam, label-wipers, and devices actuated by their

engagement with said cam for moving said wipers toward each other.

7. A labeling-machine comprising a cam, label-wipers, and spring tensional or yielding devices actuated by their engagement with said cam for moving said wipers toward each other.

8. A labeling-machine comprising movable supports, non-rotary wipers, and universal joints between the wipers and the supports.

9. A labeling-machine comprising movable supports, non-rotary wipers, universal joints between the wipers and the supports, and springs for yieldingly positioning the wipers.

10. A labeling-machine comprising movable supports, non-rotary wipers, universal joints between the wipers and the supports, springs for yieldingly positioning said wipers, and stops for limiting the movements of said wipers.

11. A labeling-machine comprising supports, wipers pivotally supported on said supports to swing longitudinally of the bottle being labeled, and springs between said supports and said wipers.

12. A labeling-machine comprising flat non-rotary label-wipers, pivotal arms supporting said wipers, a gimbal-joint between each wiper and its support, and stops for limiting the inward movement of said arms.

13. A labeling-machine comprising label-wipers, pivotal arms supporting said wipers, and stop-bars having flat faces to engage the edges of the arms and limit the inward movement of said arms, said bars being adjustable in an arc about the pivots of said arms to pre-

serve the parallelism of said flat faces with the said edges of the arms.

14. A labeling-machine comprising a lower rest or plunger, a tubular bar for said rest or plunger in which the latter is movable, a spring in said bar for cushioning said rest or plunger, a tubular guide for said bar, and means for positively reciprocating said tubular bar.

15. A labeling-machine comprising pasting means, a label-box, a type-bar, and mechanism for causing said type-bar to intermittently engage the labels in the label-box, said mechanism including a pinion, and a gear-⁴⁵ segment.

16. A labeling-machine comprising pasting means, a label-box, a type-bar, and mechanism for causing said type-bar to intermittently engage the labels in the label-box, including an eccentric, an eccentric-strap immediately connected to the type-bar, and mechanism for rotating said eccentric.

17. A labeling-machine comprising a frame, pasting means, a label box or holder, a label-carrier, a power-shaft for actuating said carrier, and printing mechanism for printing the labels including a type-bar pivoted to said frame, and operative connections between said type-bar and said power-shaft.

In testimony whereof I have affixed my signature in presence of two witnesses.

RUDOLPH F. STÄHL.
